UNITED STATES PATENT OFFICE.

SAMUEL HENRY SUMMERSCALES, OF WINNIPEG, MANITOBA, CANADA.

METALLIC WHEEL.

1,078,522.

Specification of Letters Patent. Patented Nov. 11, 1913.

Application filed June 26, 1912. Serial No. 705,993.

To all whom it may concern:

Be it known that I, SAMUEL H. SUMMERSCALES, a subject of the King of Great Britain, and a resident of Winnipeg, in the 5 Province of Manitoba and Dominion of Canada, have invented a new and Improved Metallic Wheel, of which the following is a full, clear, and exact description.

My invention relates generally to metallic 10 wheels, and, more particularly, it is directed to an improved rim construction especially intended for use with wheels such as described and claimed in my pending application No. 637,492, filed July 8, 1911.

15 The principal object of my invention is to provide a new and improved means of securing the sections of a metal rim together, whereby such rim will withstand rough usage and will efficiently perform its duties.

20 Reference is to be had to the accompanying drawings, forming part of this specification, in which similar characters of reference denote corresponding parts in all the views, and in which—

25 Figure 1 is a top plan view showing the completed wheel; Fig. 2 is a vertical sectional view showing the construction for joining sections of the rim; Fig. 3 is a detailed view; Fig. 4 is a perspective of the reinforcing or bracing element which engages 30 the adjacent ends of the sections.

The wheel comprises any suitable hub 1 and rim 2, with the spokes 3 and braces 4. These parts are all preferably of metal, the 35 rim 2 being channeled, whereby the opposite sides are provided with flanges 5. The rim is provided with a number of openings 6 varying in number and size depending on the rim, these openings being preferably 40 formed by cutting the material and bending the cut portion 7 inwardly, as shown particularly in Fig. 1. Such construction of the rim or tire increases the tractive effort since the tendency to slip is avoided, the relatively 45 soft material of the road or pavement over which the wheel is passing engaging in these openings 6, thereby providing, as it were, fulcrums about which the wheel successively moves.

50 The adjacent ends of the sections of the

rim or tire 2, and the method of joining them, are shown particularly in Fig. 2. Each end of the adjacent sections is provided with a recess 6', the depth of each of which is substantially one-half the length 55 of the opening 6, the combined depths being therefore equal to the length of the openings 6, the material removed in order to form these recesses being inwardly bent and shown at 7'. These inwardly bent portions 60 adjacent the meeting ends of the sections co-operate with the brace shown particularly in Fig. 4 in maintaining the sections in engagement. This brace is preferably of U-shaped construction, embodying the intermediate portion 8 and the sides 9, the width of the intermediate portion being substantially equal to the distance between the insides of the flanges 5 of the rim; the sides 9 are provided with openings 10 adapted to 70 register with other openings formed in the flanges 5, rivets or bolts 12 being passed through these registering openings in order to hold the brace securely in position between the flanges. The intermediate portion 75 8 of the brace is provided with an opening 11, the dimensions of which are such that when the brace is positioned as indicated, the inwardly bent portions 7' at the adjacent ends of the tire sections will engage within opposite portions of this opening, whereby such engagement tends to strengthen the joint and at the same time to properly position the brace between the flanges. 80

While the method of joining the sections of the rim or tire is particularly adapted for the metal wheel described and claimed in my co-pending application identified, it is, of course, clear that such method may be 85 employed in wheels having metal tires or rims generally.

Having thus described my invention, I claim as new, and desire to secure by Letters Patent:—

The combination of a wheel rim of inverted U-shape in cross section and having its ends provided with recesses to form an opening and with inwardly projecting integral members extending from the end walls 100

of said recesses, and an inverted U-shaped brace having an opening therein and arranged within the rim with the inwardly projecting members of said rim extending through the opening thereof, and fastening means passing through the side members of the rim and brace.

In testimony whereof I have signed my name to this specification in the presence of two subscribing witnesses.

SAMUEL HENRY SUMMERSCALES.
